F. M. WHITE.
COIN HOLDER FOR SATCHELS.
APPLICATION FILED MAR. 11, 1914.

1,108,292.

Patented Aug. 25, 1914

UNITED STATES PATENT OFFICE.

FRANK M. WHITE, OF CANTON, OHIO.

COIN-HOLDER FOR SATCHELS.

1,108,292.

Specification of Letters Patent. Patented Aug. 25, 1914.

Application filed March 11, 1914. Serial No. 823,885.

To all whom it may concern:

Be it known that I, FRANK M. WHITE, a citizen of the United States, residing at Canton, in the county of Stark and State of Ohio, have invented a certain new and useful Improvement in Coin-Holders for Satchels, of which the following is a specification.

My invention relates to improvements in coin holders for satchels in which the receptacle portion of the device is located within the satchel and so arranged that it will not be in the way or come in contact with various articles such as commonly placed in satchels or hand bags.

The objects of the present invention are, first, to provide a simple coin holder which can be attached to a satchel, and such parts of the holder exposed whereby the coin can be released, second, to provide for replenishing the receptacle from time to time. These objects, together with other objects readily apparent to those skilled in the art are attained by the construction illustrated in the accompanying drawings, although my invention may be embodied in a variety of other forms, the construction illustrated being chosen by way of example.

In the accompanying drawing: Figure 1 is a perspective view showing my device in proper relationship with reference to a satchel. Fig. 2 is a face view of the outer plate showing the same in lowered or closed position. Fig. 3 is a similar view showing the outer plate in elevated position. Fig. 4 is a perspective view of the coin receptacle showing the top or cover removed. Fig. 5 is a perspective view of the coin receptacle showing the same in a different position from that shown in Fig. 4. Fig. 6 is a detached perspective view of the top or cover. Fig. 7 is a section on line 7—7, Fig. 5. Fig. 8 is a section on line 8—8, Fig. 5. Fig. 9 is a detached perspective view of one of the push bars and one of the coin removing levers or blades. Fig. 10 is a view showing portions of the inner and outer plates showing the same spaced from each other.

Similar numerals of reference indicate corresponding parts in all the figures of the drawings.

In the accompanying drawings, 1 represents the satchel which may be of any kind such as commonly used by persons traveling short distances and more specifically to that class known as hand bags. The body of

the receptacle is made up of the front plate 2, the bottom plate 3, the rear plate 4 and the angled plate 5, said parts being bent into the form as best illustrated in Figs. 7 and 8. The front plates 2 and the back plates 4 together with the bottom plate 3 constitute a receptacle for various denominations of coin, which receptacle is divided into compartments by the partition plates 6, the number of partition plates varying, reference being had to the number of receptacles or compartments designed or desired to be used. The body of the coin holder is placed in the bottom of the satchel and preferably under the inner lining so that it will not interfere with articles designed to be placed in the satchel and for the purpose of protecting the coin, the cover 7 is provided which cover is secured in any convenient and well known manner to the receptacle body.

The front plate 2 has slidably mounted thereon the coin retaining and releasing plate 8, which is located upon the outside of the satchel as illustrated a suitable opening being formed in the satchel, which opening is closed by the plates 2 and 8. The outer plate 8 is slidably connected to the plate 2 by means of the flanges 9, which flanges are bent around the ends of the plate 2 as best illustrated in Fig. 4. For the purpose of providing a means for moving the sliding plate 8 up or down, a wire is provided which wire is made up of the spring knob portion 10, the rearward extended portions 11 and the connecting portion 12, said connecting portion being pivotally connected to the rear plate 4 by means of the ears 13, which ears may be partially cut from the plate 4 and bent at right angles and provided with suitable apertures 14, through which the connecting portion 12 of the wire passes. The plate 2 is provided with a vertical slot 15 and the upper and right angled slots 16. The outer plate 8 is provided with the horizontally disposed elongated slot 17, through which slot the spring knob portion 10 passes and is extended into the slot 15. When it is desired to adjust the plate 8 in either direction the knob portion is moved in the direction desired to move the plate 8 and when brought to the desired position the spring end of the knob 10 engages the upper or lower slot 16, thereby holding the plate 8 in the desired adjustment.

For the purpose of placing coins in

the receptacle the front plate 2 and the adjustable plate 8 are provided with the coin slots 18 and 19, and when the plate 8 is in its elevated position or the position 5 illustrated in Fig. 3 the coins can be placed in their proper receptacles. For the purpose of removing the coins from time to time as desired, push levers 20 are provided, which push levers are pivotally connected to the top or upper side 10 of the bottom plate 3 intermediate their ends and at one end of each of the push levers are attached bars 21, which bars are bent upward at their forward ends and connected or formed integral with the push bars 22, which push bars are normally held outward by means of the springs 23, which springs abut against the rear plate 4 and the upper bent portion of the bars 21 or their 15 equivalents. The levers 20 are so arranged that when the push rods 22 are in their outward positions, said levers will be in their innermost positions and back of the lowermost coin contained in the various compartments of the receptacle proper. When it is desired to remove a coin the outer plate 8 is moved upward as illustrated in Fig. 3, thereby 20 opening the coin delivery slots 24, after which the desired push bar 22 is forced inward; thereby rocking the levers 20 upon their pivotal points and forcing the desired coin forward and through the delivery slots 24.

It will be understood that when the plate 35 8 is in its lowered position or in the position illustrated in Fig. 5, the delivery slots 24 are closed and no coins can be removed from their various compartments. For the purpose of preventing any tilting movement 40 of the plate 8 when it is lifted or lowered the apertured flanges 25 are provided which are bent at right angles from the flanged portions 9, and by which arrangement the lifting of the wire or more specifically the 45 knob 10, the outer plate 8 will be moved or carried at both ends, thereby preventing any tilting or binding action.

It will be understood that in order to provide means for moving the outer plate 8 up 50 or down the slots 26 must be provided which are formed of sufficient width to allow the proper movements of the outer plate 8. The rearmost plate 5 of the body is spaced a certain distance from the plate 4 so that the 55 push rods 22 can be forced inward without interfering with any part of the satchel.

It will be understood that the push rods 22 are so arranged that they will slide back and forth through suitable apertures formed 60 in the plate 4. It will also be understood that the push rods 22 should be provided

with suitable knobs or push heads 27, which may be formed by bending a portion of the extreme outer ends of said push rods at right angles to the remaining portions of 65 said push rods, said push knobs serving the double purpose of knobs and stops, whereby the inward movements of the push rods are limited, by reason of said push heads coming against the face of the outer plate 8. It will 70 be understood that the inward movement of said push rods should be sufficient to move the levers 20 a sufficient distance to force the desired coin through the slots 24. The wire is made up of the various members constituting what might be termed a bail or yoke so formed and connected as to move the adjustable plate.

Having fully described my invention what I claim as new and desire to secure by Letters Patent, is—

1. In a device of the character described, the combination of a coin receptacle consisting of front, bottom and rear plates and an angle plate, said receptacle provided with 85 partition plates, said front plate provided with coin receiving and delivery apertures, an outer plate provided with coin receiving apertures adapted to register with the coin receiving apertures in the front plate and 90 adjustably connected to said outer plate of the receptacle and means for holding said adjustable plate in fixed adjustment, a series of coin delivery levers pivotally attached to the coin receptacle and means for 95 actuating said coin delivery levers, substantially as and for the purpose specified.

2. In a device of the character described, the combination of a coin receptacle consisting of front, bottom and rear plates and 100 an angle plate, said receptacle provided with partition plates, said front plate provided with coin receiving and delivery apertures, an outer plate provided with coin receiving apertures adapted to register with 105 the coin receiving apertures in the front plate and adjustably connected to said outer plate of the receptacle and means for holding said adjustable plate in fixed adjustment, a series of coin delivery levers pivotally attached to the coin receptacle and means for 110 actuating said coin delivery levers, said means for actuating the coin delivery levers, said means for actuating the coin delivery levers in one direction extended through the front and adjustable plates. 115

In testimony that I claim the above, I have hereunto subscribed my name in the presence of two witnesses.

FRANK M. WHITE.
